INDOOR GOLF BALL PUTTING APPARATUS

Frank Fortino, Newark, N. J.

Application February 17, 1954, Serial No. 410,835

1 Claim. (Cl. 273—180)

This invention relates to a golf game device for indoor putting, wherein strip material of raised contour is employed in a novel outline-defined zone-scoring area indicator. More specifically, it includes an integral 3-zone marker in which the zones decrease in area progressively away from the player.

The invention may be more readily understood by reference to the accompanying drawings in which Figure 1 depicts a preferred embodiment of a 3-zone marker for indoor putting. Figure 2 shows a view in perspective of the strip outline material from which the marker preferably is made, another embodiment of which is illustrated in Figure 2A. Figure 3 is a cross-sectional view of the strip illustrated in Figure 2. Figures 4 and 5 show other modifications of zone markers of the type shown in Figure 1. A putting game using the marker devices of the present invention is depicted in Figure 6. Similar numerals refer to similar parts in the various figures.

Referring again to the drawings, numeral 1 represents the preferred zone marker which is made of combined zone outlines of strip material 16 which is laid on the floor in the position shown in Figure 2, so that the edges 18 touch the floor or rug, while the arcuate hump 17 serves as an area limiting means for the golf ball. The ball either rolls over the hump or rolls back from it, thereby allowing accurate determination of the zone in which the ball is to be scored. The inside of the arcuate portion of the strip may be filled with sponge rubber 38 or other similar material, as in Figure 2A.

The zone marker 1 comprises an outline configuration comprising three border-sharing interconnected zones, each diminishing in size with increasing distance away from the player. The nearest and largest zone 3 is defined by long sides 2, bottom strip 5 and shorter interconnecting sides 4, all of which preferably are of yellow colored arcuate interconnected strips 16. When a golf ball is putted into this zone, it brings the par score (equivalent to four strokes).

The next succeeding zone 6 which is farther away from the player and is smaller than zone 3 in area, is defined by sides 7, 8, 9, etc., which preferably are made of strips 16 colored green. This zone is interconnected with the sides of zone 3 at 14. When a ball is putted into this zone, it represents a birdie, or a stroke under par (3 strokes).

The last and most difficult zone of marker 1 to putt into is zone 10 defined by sides 11, 12, 13, etc., which are made of strip material 16, preferably colored orange. This zone is interconnected with zone 6 at 15, is smaller in area and is farther away from the player. A ball putted into zone 10 represents an eagle, or two strokes under par. Zones 3', 6' and 10' are equivalent zones for the marker depicted in Figure 5, while zones 3", 6", and 10" are equivalent zones for the marker shown in Figure 4.

The game is played on a simulated green laid out as in Figure 6. The playing area of the green is outlined

2

in a rectangular area by straight strips (similar to strip 16) and numbered 23, 24, 25, 26, 27, 28, 29, 30, 31 and 32. Balls played within this area not rolling into any zone markers represent a score of a stroke above part or a bogie 1. Balls rolling outside of the rectangle 24, 27, 29, 32, etc. (or out of bounds), represent a score of two strokes above par (or bogie 2). The small circles 19 (also of material similar to strip 16) represent a score equivalent to a hole-in-one (here called a zone-in-1).

The player begins to play by placing his golf ball near but outside of playing zone No. 6 which is numbered 37. He then puts the ball with a putter to playing zone No. 1 (or marker 1). If the ball rolls into the area of marker 1 equivalent to the par area (or area 3 in Figure 1), he obtains a par score (4 strokes). He then must play the circle bearing the same color, or circle 21 for the opportunity of making a birdie (or reducing his score by one point). If he fails to putt into circle 21, he retains the par score and then moves the ball in the vicinity of playing zone No. 1, from which he then puts for marker 33 in playing zone No. 2, and the procedure is continued in numerical sequence.

If, in putting for marker 33, the player puts the ball into the birdie area of marker 33, the player must then play for the circle of the same color, or birdie circle 22. If this is made, the score is an eagle (or 2) for the stroke. In other words, the player always plays the marker which will lower his stroke score by one point. If the player puts into the eagle area of marker 33, he follows by playing for the marker in the next playing zone (No. 3).

If a player misses a zone in a marker, he must play for the white circle 20 to get a par score. If he fails to putt into circle 20, he has a bogie 1 for the score (5). If the ball rolls out-of-bounds (outside of the straight strip markers 24, 25, 26, 27, 28, 29, 30, 31, etc.), the player must putt into the "neutral" circle 20 to reduce his score from bogie 2 (or 6) to bogie 1. Any balls entering small blue circles 19 are considered as zones-in-one. Par for the course is 72 for 18 playing zones (or three times around those in Figure 6).

Strip material 16 preferably is of thin tempered steel, but it may be of aluminum, plastic, or other suitable material. The markers may be made of one-piece stamped strip material, of the type depicted as numeral 16, or they may be hinged at various points for greater flexibility to conform with the floor or rug.

The circle markers may be disposed at various predetermined locations on the simulated green, although the disposition shown in Figure 6 is preferred.

I claim:

An indoor golf-scoring device comprising a portable, interconnected, narrow-strip, triple space-enclosing marker having a first uniplanar, convex-top strip portion constructed and arranged to enclose partially a first relatively large space, a second uniplanar, convex-top strip portion constructed and arranged to enclose partially a second intermediate size space and to complement, by means of a portion thereof projecting into said large space, the complete enclosure of said large space, and a third uniplanar, convex-top strip portion constructed and arranged to completely enclose a third relatively small space and to complement, by means of a portion thereof projecting into said intermediate space, the complete enclosure of said intermediate size space, said third space being disposed centrally of said second space and being of such dimensions that relatively large areas of said second space lie on opposite sides of said third space.
